Application May 26, 1945, Serial No. 596,014

5 Claims. (Cl. 161—15)

1

This invention relates to improved chronographic apparatus and methods and more particularly to apparatus and methods for timing events at exceedingly short intervals. The apparatus and methods of the invention are of particular usefulness in measuring and recording the performance of ordnance projectiles and is hereinafter specifically described with reference to such work, although it must be understood that such specific application is merely illustrative.

It is an object of the invention to provide improved chronographic apparatus and methods and particularly to provide apparatus and methods for accurately indicating and recording time intervals of exceedingly short duration and utilizing photoelectric pick-up apparatus. It is also an object of the invention to provide apparatus and methods of indicating and recording the performance of ordnance projectiles and other rapidly moving objects. Another object is to provide improved circuit apparatus and methods, and sensitive photocell pick-up devices.

Other and further objects are those inherent in the apparatus hereinafter illustrated, described and claimed.

The invention is illustrated with reference to the drawings in which

Figure 1 is a schematic plan view of the system;

Figures 2 and 3 are, respectively, front and side elevational views of a light source with its power supply and standard that is used in the system in conjunction with a photocell apparatus, illustrated in Figures 5 and 6;

Figure 4 is an enlarged detail of the photoelectric cell support;

Figures 5 and 6 show, respectively, front and side elevational views of the sensitive photocell pick-up, self-contained amplifier and power supply and standard therefor;

Figure 7 is a wiring diagram of the light source and power supply therefor;

Figure 8 is the wiring diagram of the photocell and its associated amplifier;

Figure 9 is the wiring diagram of the power supply and output trigger tube apparatus of the photocell pick-up;

Figures 10 and 11 are, respectively, front and side elevational views of the indicating and recording instrument;

Figure 12 being a fragmentary vertical sectional view of a part of this apparatus taken along the line 12—12 of Figure 10;

Figures 13 and 14, taken together, show the wiring diagram of the indicating and recording

5

instrument, and the amplifiers, power supply, switching and testing apparatus therefor. Figure 13 should be placed at the left and Figure 14 at the right so as to show the complete diagram;

Figures 15 and 16 are, respectively, front and side elevational views of the amplifiers, power supply, switching and testing apparatus; and

Figures 17, 18 and 19 are diagrammatic views showing, respectively, the "Read," "Range" and "Disjuncture" operating condition switches I-X of the station unit.

Throughout the drawings corresponding numerals refer to the same parts.

General arrangement, Figure 1

Referring to the drawings, Figure 1 shows a schematic plan view of an illustrative installation, in this case specifically an ordnance test firing range. The ordnance piece undergoing testing is shown at 18, and may, for example, be a small arms rifle such as a 30 caliber or 50 caliber machine gun or a larger piece. The rifle, if such be the ordnance piece undergoing testing, is mounted in fixed position and fires down the range, along line 11—11 into a sandbag or other suitable bunker 12. Along the line of projectile flight there are two spaced pick-up stations, namely the muzzle station 13 and the range station 14. At the muzzle station there is a light source unit 16 and a photocell and amplifier unit 18, and at the range station an identical light source unit 20 and identical photocell and amplifier unit 22. The photocell units 18 and 22 and the light source units 16 and 20 are supplied with power by alternating current supply lines designated L₁ and L₂. The output (signal) from the photocell-amplifier 18 and muzzle station 13 is transmitted to the station unit 25 by means of a pair of signal lines K and G, line G being grounded as indicated at 26. Similarly the output (signal) of the photocell-amplifier unit 22 is transmitted to the station unit 25 by means of lines N and G', the latter being grounded at 27. The various units and their mode of interconnection and operation will be described in greater detail hereinafter.

Light source units 16 and 20, Figures 2, 3 and 7

The range and muzzle station light source units 16 and 20 are identical and are illustrated in Figures 2, 3 and 7. These units are made movable and include a base generally designated 30 to which is welded an upright standard generally designated 31. Base 30 consists of a housing 32 adequately braced and provided with a floor 35. The housing is preferably open at one side to re-

ceive a steel case 38 housing the power source of the light, as hereinafter described. Case 38 is preferably made of strong metal, heavy walled, and may have a ventilating grill 37 if heat losses are not adequately dissipated by radiation.

The upright standard is conveniently a simple steel channel 38 of U-shaped cross section having a pair of webs 39 and 40 welded thereacross to support the sockets 41 and 42 of the lumiline type lamp 43. A pair of conductors 44-45 are draped in the channel and are thus protected, the conductors extending down into the power supply case 38.

Figure 7 shows the wiring diagram of the light source units 16 and 20. Line L₁ is fed from line L₁' through a fuse 47 and switch 48 which may conveniently be located at the station unit 25. One switch 48 and fuse 47 usually suffices for all of the light source units 16, 20 and such others as may be used, although individual controls may be used, if desired. Line L₁ is connected to one terminal of the primary winding 49 of transformer 50, and is also connected through line 52 to the anode or anodes 53 of the rectifier tube 54. Line L₂ is connected to the other terminal of winding 49 and thence through junctions 55, 56 and line 45 to the lumiline lamp 43, whence the circuit continues through line 44, to junction 57 and thence through iron cored reactor 61 and junction 58 to terminal 63 of the secondary 51 of the transformer. The filament (cathode) 65 of tube 54 is connected directly across the secondary winding 51. Capacitors 59 and 60 are connected across the direct current output lines on either side of the reactor 61, as shown. In operation the transformer 50, rectifier 54 and the filter composed of capacitors 59 and 60 taken with reactor 61 serve to supply smooth direct current at appropriate voltage across lines 44 and 45, thus energizing lamp 43 so as to produce a uniform degree of illumination. Flashing of the light or stroboscopic effects when lamps are energized from an alternating current line are thereby avoided. This is important in the very sensitive photoelectric application here illustrated.

The photocell units 18 and 22 occupy positions directly across from their cooperating light sources 16 and 20, respectively, as shown in Figure 1 and are positioned so as to intercept light from the lamp 43 of the light unit. Photocell unit 18 is arranged to intercept light projected in the direction of line 70-71, while photocell unit 22 intercepts light in the direction of line 73-74. The lines of light 70-71 and 73-74 are across the path of flight of the projectile, hence the movement of a projectile from the piece 10 towards bunker 12 causes an instantaneous decrease in light falling on photocell 18 and a short interval later, depending upon distance D, Figure 1, and the velocity of the projectile, a similar instantaneous decrease occurs at photocell 22.

The time duration of these periods of decreased light intensity and the percentage variation in light intensity are both exceedingly small. Hence, a high degree of sensitivity and rapidity of response are requisite freedom from interference and accurate signal transmission. To accomplish these purposes there are provided the photocell, amplifier and power supply units 18 and 22.

*Photocell, amplifier and power supply units
18 and 22, Figures 5, 6, 9 and 10*

For the purposes of the specifically illustrated

embodiment of the invention, viz. ordnance testing, the photocell units 18 and 22 may be identical; hence only one need be described.

The combined photocell, amplifier and power supply unit 18 or 22 includes a base 75 and standard 76 of construction and dimensions similar to that illustrated for the light source. The base 75 includes a housing 78 stiffened with angle iron which may be open at one side to receive the power supply case 82, which is made of stout sheet metal and provided with grill 83. The case rests on the welded in floor 85. Post 76 is of square or round hollow steel tubing, terminating in a box-like amplifier case 87 which has a front cover 88 removably attached thereto. On top of the amplifier case 87 there is mounted a smaller steel cupola 90. An opening 95 from the top of the amplifier case into the cupola is provided so as to allow the photocell which is mounted on the amplifier to be inserted. The cupola 90 has a light aperture 93, behind which is positioned the photocell. Case 91 forms a complete shield for the photocell, which is exposed to light only through window 93. Wiring from the power supply case 82 to the amplifier case passes through the hollow post 76 and the support and wiring between the amplifier and photocell passes through the small interior opening, not illustrated, between these cases. Each unit is thus completely shielded electrically and is so ruggedly mounted that sound and other mechanical vibrations produce no deleterious effects in the circuits. The light source units 16 and 20 and the photocell units 18 and 22 are painted black inside and out.

Figure 8 is a wiring diagram of the photocell and amplifier chassis which is mounted in case 89 and cupola 90. This unit includes a base 100 which physically supports two heavy walled boxes 101 and 102 which serve in turn as electrical shields and cases for the several amplifier stages. Boxes 101 and 102 are supported on sponge rubber pads 103 and 108 so as to damp out mechanical vibrations. Base 100 serves also to mount a connection socket 104 having terminals 1 through 8 which serve to connect the amplifier-photocell instrument, Figure 8, to the power pack and thyratron trigger tube unit, Figure 9. These terminals have the following purposes: Terminals 1 and 8 supply filament current for the three amplifier tubes of Figure 8. Terminals 2, 4 and 6 are connected together and to ground through ground lines hereinafter traced. Terminal 3 supplies high voltage direct current (in this illustration, specifically 380 v. D. C.). Terminal 7 supplies an intermediate direct current voltage (in this illustration, specifically 90 v. D. C.). Terminal 5 carries the signal output of the amplifier, Figure 8, to the gas-filled trigger tube (thyratron) in the unit, Figure 9.

The entire unit composed of base 100, shield boxes 101 and 102 and photocell 105 is housed in the box 87 and photocell cupola 90. Box 90 may be provided with an extra ground via line 106 to ground 101.

From the top of shield 101 there extend two copper tubes 110 and 111 which are positioned on shield 101 so that they will reach through port box 87 into the photocell cupola 90 when the chassis 100 is in place in the unit. Conduits 110 and 111 serve to support the photocell 105 and also serve as electrical shields for conductors 129 and 136 extending down from the photocell into the amplifier. As shown in Figure 4, the conduits 110 and 111 are provided at their lower ends with female gland nuts 110' and 111' which

are spaced so as to fit the male gland studs 110" and 111" on the shield case 101. At their upper end, tubes 110 and 111 are brought together and soldered to the center post 113 of socket 117. Lead wires 129 and 136 extend from terminals 129a and 136a (at the lower ends of conduits 110 and 111) through the conduits and thence to terminals 129' and 136' on the socket. The photoelectric cell 105 is simply plugged into the socket 117 when servicing or renewal is desired. It may be noted that conduits 110 and 111 extend up closely to socket terminals 129' and 136' but do not touch them, thus providing shielding as well as mechanical support to a position close to the socket, the mechanical support being then carried through post 113.

From the intermediate voltage direct current supply terminal 7, plug 104, line 114 extends through resistor 115 to terminal 116 whence the circuit continues along ground line 118 through junction 119—126. A branch of line 118 extends to junction 127 which grounds line 118 to case 101 and thence to ground terminals 2, 4 and 6 on plug 104. From variable positive tap 128 line 129 extends through junction 130 and through the conduit 110 to the anode 133 of the photocell 105. The circuit extends from the cathode 134 of the photocell through line 136 to junction 137 and thence through capacitor 138 to junction 139 which is connected by line 140 to control grid 143 of the pentode amplifier tube generally designated 141.

The tube 141 has a cathode 142 indirectly heated by filament 147, control grid 143, a second grid 144, a screen grid 145 and a plate 146. From junction 139 on line 140 a circuit extends through resistor 148 to junction 149 and thence to the negative terminal of a bias cell 150. The circuit extends from the positive terminal of the bias cell 150 through resistor 151 to junction 119 on the ground line 118. A condenser 153 is connected from the negative terminal 149 of the bias cell to junction 120 on the ground line 118. From junction 137 a circuit extends through resistor 121, thence through junction 131 to ground terminal 116. A condenser 132 is connected across terminals 130 and 131, thus bridging the major part of resistor 115.

From junction 121 on the ground line a circuit extends through line 154 to cathode terminal 155 and thence to the cathode 142 of amplifier 141. The screen grid 145 is connected to the cathode terminal 155. The second grid 144 is connected through line 157 to junction 158 and thence through resistor 159 to junction 160, from which the circuit extends through line 161 and condenser 162 to junction 124 on the ground line 118. From junction 158 on the lead 157 of grid 144, a circuit extends through line 163 to junction 164 and thence through a continuation of line 163 and condenser 165 to junction 122 on the ground line 118. To junction 164 there is connected a resistor 167, the opposite terminal of which is connected to junction 123 on the ground line 118. The plate 146 of the amplifier tube 141 is connected through line 169 to junction 170 and thence through condenser 171 and through resistor 172 to junction 126 on the ground line 118. A circuit extends from junction 170 through resistor 173 to junction 174 and thence through resistor 175 and line 176 to the high voltage terminal 3 of the connection socket 104. Junction 174 is connected through line 178 to junction 160.

Amplifier tubes generally designated 180 and

220 are housed in the sheet metal box 82. Amplifier tube 180 has a cathode 181 indirectly heated by filament 187, a control grid 182, a second grid 183 and a screen grid 184 and plate 186. The control grid 182 is connected through line 188 which is shielded throughout its length by means of shield 189. The line 188 extends to a variable tap 190 on the resistor 172 of the first stage of amplification. The cathode 181 is connected through line 191 to terminal 192 and thence through the resistor 193 to terminal 195 on the ground line 194. The ground line 194 is grounded at 196 upon the metal case 192, the line 194 being extended to terminal 6 of the connector socket 104. From junction 192 a circuit extends through condenser 202 to junction 197 on the ground line 194. The second grid 183 and screen grid 184 are connected together externally and are connected through line 204 to junction 205 on the plate lead 206. The plate lead 206 extends through junctions 205 and 207 and through condenser 208 and thence through line 209 and resistor 210 to junction 199 on the ground line 194. From junction 207 on the plate lead a circuit extends through resistor 211 to junction 212 and resistor 213 to junction 214 on the (high voltage) supply line 215 which is connected to junction 177 on line 176. A condenser 216 is connected across junctions 212 and ground terminal 198.

The third stage of amplification is represented by amplifier tube 220 which has cathode 221 indirectly heated from filament 222, a grid 223 and plate 224. The grid 223 is connected to junction 225 on line 209, the cathode 221 being connected through line 227, junction 228, resistor 229 to terminal 200 on ground lead 194. A condenser 230 is connected around resistor 229 from junction 228 to ground terminal 201. The plate circuit of tube 220 extends from plate 224 through line 231, junction 232 and thence through resistor 234 to junction 235 and resistor 236 to high voltage supply via line 215. A condenser 238 is connected from junction 235 to ground terminal 201. The output circuit of amplifier tube 220 is through condenser 240 and line 241 to terminal 5 on the socket 104.

Referring to Figure 9 there is illustrated the combined wiring diagram of the gas-filled trigger tube and the power supply chassis. The power supply serves not only that trigger tube 284 but also the amplifier and photocell circuits of Figure 8. The entire apparatus of Figure 9 is mounted on a suitable base and is housed within the box 82 on the base of the unit, Figures 5-6. The incoming circuits to the unit of Figure 9 include an alternating current power supply lines L₁ and L₂ which connects to a socket 242 of such construction that there can be no reversal of these leads since one of the leads (L₁) is grounded. From terminal (line L₁) 243, line 244 extends to primary winding 245 of transformer 246, from which the circuit continues through line 247, fuse 248, switch 249 to terminal 250 and line L₁. The transformer has a filament winding 252, the center tap being connected by line 253 to housing ground 254. The outside terminals of winding 252 are connected by lines 255 and 256 to terminals 1 and 8, respectively, of the plug 104A which matches socket 104 of drawing Figure 8. Transformer 246 is provided with a plate voltage winding 257 and a filament voltage winding 261 which are connected to rectifier tube 262 in the customary manner as follows: Winding 257 is connected to the two plates of

the rectifier and winding 261 to filament 263. The rectifier negative output line 265 is connected to the midpoint 258 of transformer winding 257 and extends to the negative terminal 267 of the potentiometer resistor 269. The positive line of the rectifier 262 extends from the filament secondary winding 261 through line 266 and extends through a choke coil 270 to the positive terminal 271 of the potentiometer resistor. A pair of condensers 272 and 273 are connected across the lines 265 and 266 and the chokes serve to smooth out the rectified direct current output.

The potentiometer resistor 269 is provided with tap 274 which is connected to the housing ground 284. The negative line 265 is, in the specific device here illustrated, approximately 40 volts negative. The resistor is also provided with a variable tap 275 of approximately 90 volts, a variable tap 276 of approximately 180 volts and a high voltage tap 277 of approximately 380 volts. Tap 275 is connected by line 280 to terminal 7 on the plug 104A and the high voltage tap 277 is connected by line 281 to terminal 3 of the plug. Terminals 2, 4 and 6 of the plug are connected together and are connected by line 282 to the grounded tap 274 of the potentiometer resistor.

A gas type trigger tube generally designated 284, having cathode 285, cathode heater filament 286, grid 287 and plate 288 is connected so as to be controlled by the incoming signals on terminal 5 of plug 104A. Terminal 5 is connected by line 290 to junction 291 and thence through resistor 292, switch 293, junction 294 to the control grid 287 of the tube. The cathode 285 of the tube is connected through resistor 296 to junction 297 on the ground line, resistor 296 being paralleled by the condenser 299. The resistor 296 is also arranged in parallel with a neon indicator light 300 which is connected through switch 301. From tap 276 on the potentiometer resistor line 283 extends through resistor 304 to junction 305 on the plate circuit 306 of the trigger tube and the circuit continues over line 307, through condenser 308 and thence through junction 309 and resistor 310 to junction 311 on the ground line 282. Junction 309 serves as the output terminal and is connected by line 313 to the output terminal 314 on the output plug generally designated 315. A plug connection to socket 315 carries a ground line and a signal line. These are the pairs G and K or G' and N of Figure 1. Terminal 316 of the output plug is therefore grounded at the station unit 25 and hence line 317 extending from socket 315, Figure 9, serves as a ground for that unit and also for the parts shown in Figure 8 since these are all in the standard illustrated in Figures 5 and 6. Line 317, Figure 9, extends to junction 318 on the central tap lead 253 of the filament supply transformer, and thence through line 253 to junction 320 on the housing ground line 254. From junction 294 on the grid line of the trigger tube a circuit extends through resistor 322 to junction 323 on the ground line and from junction 291 of the grid resistor 292 a circuit extends through resistor 324 to a variable tap 325 on resistor 326. Resistor 326 is connected to junction 327 on ground line 282 and is connected through line 328 to the negative terminal 267 of the potentiometer resistor. A condenser is connected between junction 327 on the ground line and junction 330 on line 280.

Station apparatus

The station unit 25 includes the apparatus

shown in Figures 10-12 and also the apparatus shown in Figures 13-16.

Figures 10, 11 and 12.—Referring to Figures 10, 11 and 12 there is illustrated a unit having a base 335 generally designated 335 on which is mounted a synchronous motor 336 which is coupled at 337 to the shaft 338, the latter being supported in a pair of bearings 339 and 340, Figures 11 and 12. To the front of the base 335 there is fastened a vertically positioned disk 342 which is attached in place by a plurality of cap screws 343. The disk 342 serves as a mounting for the bearing 340, Figure 12, and on the front end of the shaft 338 there is mounted a rotating unit generally designated 345. The unit 345 is of non-magnetic material and in its periphery is a groove which receives a very thin ring 347 of magnetic material which is fastened in place by any suitable means. The ring 347 of magnetic material serves to have impressed upon it the timing impulses.

On the front of the disk 345 there is mounted a dish-shaped cover 348 which serves to mount a neon lamp 349 on the inside which is visible through a small aperture 350. The cover is grooved at 352 and the groove is painted black so as to correspond with the black inside 353 of the housing in which the neon lamp is situated. One terminal of the neon lamp is grounded and the other terminal is carried out through lead 355 to a central stud 356 against which the spring contact 357 presses. Contact 357 is mounted upon an upright member 358 of clear plastic or any other suitable material so that the flash of the neon lamp will be visible through it. An incoming lead wire D is connected to the terminal 357 so as to conduct the incoming signal wave to the neon lamp.

The disk 342 is provided with a bushing 360 which serves as a hub for the adjustable radial arm generally designated 361 which extends out beyond the edge of the disk. The disk is provided with an arcuate groove 363 which extends about half way around the disk and through the groove there extends a stud 365 which passes through member 361 and serves as a support for another shorter member 366 that lies parallel to but behind the member 361. Another arcuate slot 364 may be provided if desired so as to allow a fastening rivet 369 to pass through the disk. Rivet 369 serves with 365 to fasten member 366 in spaced parallel relation with the outer part of radial arm 361.

Between the protruding end 367 of arm 361, and 368 of arm 366 there is positioned a rubber roller 370 which is mounted on a shaft 372 held in place by a collar 373. On the front end of the shaft there is provided a manually adjustable knob 375. The location of shaft 372 is such that the rubber roller 370 presses against the edge 342A of the disk 342 and hence as the knob 375 is rotated, this causes the roller 370 to grip the periphery 342A and the members 361 and 366, as a unit, are moved arcuately around the disk. The periphery 342A may be knurled, if desired, to provide a good grip for the rubber roller.

Stud 365 serves as a support for a small electric coil 378, the core of which is shown at 379. The core terminates in a tip 380 which is very close to, but spaced from the magnetizable ring 347. Whenever an electrical signal is impressed upon the coil 378, the portion of the ring 347 which is then under the tip 380 is magnetized. The member 361 also serves as a mounting for the magnifying glass 381 which is located over a window in member 361 so that the graduations 342B will be readily visible therethrough. The mag-

nifying glass is provided with a sighting line 382 for purposes of accurate reading. The coil 378 is energized through a lead wire 383 which extends out of the side of the coil and through the arcuate slot 363.

At another part of the disk 342 there is mounted a second coil generally designated 385. The coil 385 is identical with coil 378 and is provided with a core terminating in a tip 386 likewise located very close to but slightly spaced from the magnetizable ring 347. Coil 385 is mounted upon a V-slot and has a sidearm 387 against which an adjusting screw 388 is adapted to bear. The adjusting screw is mounted in the clip 389. As the screw 388 is turned the arm 387 is lifted or lowered and hence the coil 385 may be moved either way along the line of the double arrow 390. A scale 391 is located alongside the coil so that its position relative to the disk can be readily determined. The coil 385 is energized through an incoming pair of lead wires 393 which are taken out through the end of the arcuate slot 363. An erasing coil 394 is mounted solidly upon the front of disk 342 and is provided with a core 395 extending close to but with slight clearance from the magnetizable ring. The erasing coil when energized with direct current that is gradually diminished, serves to erase any magnetized signals on the ring 347.

Figures 13-14.—The electrical circuits of the station apparatus are illustrated in Figures 13 and 14. When reading these diagrams they should be arranged with Figure 13 to the left and Figure 14 to the right. The apparatus of Figures 10-12 is schematically illustrated at the right end of Figure 14 which shows the synchronous motor 336 driving the disk 345 upon which the neon lamp 349 is mounted. The fully adjustable or No. 1 pick-up coil 378 which is the movable one is likewise shown along with the No. 2 pick-up coil 385 that is stationary except for slight adjustments occasioned by rotating screw 388. The erasing coil is shown at 394 and the neon light circuit connection at D. The synchronous motor is energized from alternating current lines L₁ and L₂ through switch 711, and the frequency meter 396 is connected across the lines. The frequency indication provides a basis for adjusting screw 388 and for thus imposing a slight movement of coil 385. The pick-up coil 378 is connected by means of its (shielded) cable 393 to station pre-amplifier No. 1 which is completely shielded by grounded housing 397. The shield of cable 393 is connected to this housing and the conductor to another portion, as later described. Similarly, pick-up coil 385 is connected through its shielded conductor 393 to station pre-amplifier No. 2, the shielding of the cable being connected to grounded case 398 which likewise serves to shield the pre-amplifier. The internal lead of the cable 393 is connected to the pre-amplifier No. 2 as later described.

Referring to Figure 13, under the bracket generally designated 400 there is illustrated what may be described as the thyratron chassis. In this portion of the apparatus there is included two power supplies, two gas type trigger tubes (thyatron) and a plurality of switches, preferably of the microswitch type, that are manually operated, as hereinafter described. Under the bracket 401 there is illustrated a power supply No. 1T while over the bracket 402 there is illustrated an identical power supply No. 2T. Since these power supplies are identical only one need be described as representative.

Alternating current supply is provided over lines L₁ and L₂ and switch 722, which serves to energize the primary winding 403 of the transformer generally designated 405 and also that of power supply No. 2T. It may be noted incidentally that all alternating current service lines to the installation may be served through this one switch, if desired, or separate controls may be used. The transformer 405 has a secondary 406 which serves through switch 720 to feed the filament cathode 407 of the full wave rectifier tube 408. The transformer also has a higher voltage secondary 409 which is connected to the two anodes 410 and 411 of the full wave rectifier tube 408. The positive output line 412 is connected to one side of the transformer winding 406 and the negative output line 413 is connected through switch 721 to the center tap 415 of the winding 408. Choke coil 416 and a pair of condensers 417 and 418, connected in the usual way, serve to smooth out the direct current output which is applied to a potentiometer resistor 419 having an intermediate tap 420 grounded at 421. The tap 422 is approximately 20 volts negative and the tap 423 approximately 400 volts positive. Similarly, power supply No. 2T, shown over the bracket 402, provides approximately 20 negative volts on negative output terminal 424, ground potential at tap 425 and approximately 400 volts positive at output terminal 426. A direct current voltmeter 427 having one terminal grounded at 428 is arranged to be connected through switch 714 to positive output terminals 423 and 426 of the two power supplies, in order to read either of the output voltages. An intermediate voltage tap 430 is provided on the potentiometer resistor 431 of power supply 402 and is connected through switch 432 to junction 433 and thence through resistor 434 to lead 435 which extends to the eraser coil 394, Figure 14. A ground lead 436 is connected to condenser 437 and also extends to the eraser coil. By closing switch 432 for a short time, condenser 437 is charged to the voltage of tap 430 on power supply 402. This potential is also applied through resistor 434 and lead wires 435 and 436 to the eraser coil 394. When the push-button switch 432 is opened, condenser 437 discharges through the resistor and the eraser coil, and the magnetism of this coil therefore subsides to zero value, in a time period determined by the time constant of this circuit. During erasing the disc 345 is rotated and hence a gradually decreasing magnetism is applied to the disc for the erasing operations.

Microswitches.—At the right-hand portion of each of Figures 13 and 14 there are shown a plurality of microswitches designated I-VI in Figure 13 and VII-X in Figure 14. Each of these switches has two operative positions. Switches I-VI are operated mechanically by means of cams through a single cam-actuated shaft controlled by the operator through a suitable handle 713, Figure 15. There are three sets of operating conditions for switches I-VI, as shown by Figures 17, 18 and 19. Microswitches VII and VIII are operated by an alternating current solenoid actuator V_a which is in turn energized by microswitches V. Switches IX and X are operated through an alternating current solenoid actuator V_{1a} controlled by microswitch VI. The circuits for the solenoid actuators are as follows:

Alternating current is supplied through lines L₁ and L₂ (at the center of Figure 13). Line L₁ is connected to feeder 438 which extends to junc-

tion 439 and thence to the common terminal 440 of switch V, another extension being to the common terminal 441 of switch VI. When switch V is in the position shown in Figure 13 (same in Figure 17), a circuit is completed to terminal 442, switch V, whence power is conducted by way of line 443 to the winding of the solenoid actuator Va, the return circuit to line L₂ being by way of line 444. Thus, when switch V is in the position shown in Figure 13, the coil of solenoid actuator Va is energized and the microswitches VII and VIII are held in the position shown in Figure 14. Switches VII and VIII are located within the shield 397 of pre-amplifier No. 1 and are thus isolated from extraneous electrical disturbances from coil Va or anything else. When switch V is moved against contact 445 the circuit to coil Va is broken and microswitches VII and VIII move to the opposite position from that shown in Figure 14. Similarly when microswitch VI is in the position shown in Figure 13 (same for Figure 17) a circuit is completed from line L₁ through junction 439 to terminal 441 and thence through microswitch VI to terminal 446 whence the circuit continues by way of line 448 to the coil of solenoid actuator VIa, the circuit being completed to line L₂ by way of line 444. Thus, energizing the solenoid actuator VIa holds microswitches IX and X in the position shown in Figure 14. When microswitch VI is moved to the position so that its movable contact engages the dead contact 447, the circuit to coil VIa is de-energized and the microswitches IX and X move to the position opposite to that shown in Figure 14, see Figure 18, for example.

There are three sets of operating conditions which are shown in Figures 17, 18 and 19, these three conditions being the reading conditions for the instrument marked "Read," Figure 17, the condition under which the signal from the range photocells are impressed upon the station apparatus marked "Range," Figure 18, and a testing condition under which certain tests of the instrument itself are made marked "Disjuncture," Figure 19.

The signals from the muzzle and target range stations 18 and 22, respectively, are received by way of lines K and N (Figure 1) which terminate at microswitches I and II, respectively, Figure 13. Incoming ground lines G and G' of Figure 1 are not illustrated in Figures 13 and 14. Thus, line K is connected to terminal 449 of microswitch I and when that switch is in the Range or Disjuncture positions, Figures 18 or 19, the circuit is completed to the common terminal 450 of the microswitch I, and thence through resistor 451 and condenser 452 to the primary 453 of the transformer generally designated 454. The circuit is completed to ground line 455 which is grounded at 456. The received signal from the range stations (either the muzzle or target stations) is a sharp negative wave and this induces a similar sharp positive wave in the secondary 457 of transformer 454. Secondary 457 is connected by line 458 to the negative terminal 422 of power supply No. 1T which normally maintains a negative voltage on the transformer secondary, and is also connected directly to the grid 460 of a gas type trigger tube (preferably thyratron) generally designated 461. Tube 461 is provided with an indirectly heated cathode 462, grid 460 and anode 463. The anode is connected by means of line 464 and condenser 465 to the ground line 455 and is connected through line 467 and resistor 487 to the positive termi-

nal 423 of power supply No. 1T. The transformer secondary 457 is also connected through condenser 468 to the ground line 455 which supplies a high frequency pass for the sharp wave signal induced in the secondary. Cathode 462 is connected through the primary 478 of the transformer 471 to ground line 455. The trigger tube 461 is ordinarily not conductive and the condenser 465 charges to the voltage of output terminal 423 by means of the charge line 467 in which there is located the resistor 487.

The grid 460 of the trigger tube is normally maintained negative through transformer secondary 457 and the connection 458 to the negative terminal of the power supply. When the sharp negative signal wave is impressed upon winding 453, this induces a positive signal at winding 457 which momentarily shifts the grid 460 to the positive condition, whereupon tube 461 becomes conductive and remains conductive until the charge on condenser 465 is dissipated, whereupon it ceases to conduct since there is no longer any appreciable voltage existing across the condenser 465. Resistor 487 is of high enough value that it will not supply current for continuing the discharge.

This momentary discharge surge is impressed upon the primary 478 of the transformer 471 and induces a signal current surge in the secondary 473 of that transformer through a circuit extending from ground 456, through ground line 455, thence to terminal 474 through ground line 455, thence to terminal 475, terminal 476 to the anode 477 of the full wave rectifier tube 478, thence to the cathode 479 of the rectifier tube and to the terminal 480 of the cathode heater supply transformer. The circuit continues through resistor 481 and line D to the neon tube 349 on the revolving disc and thence to ground. Thus, an incoming signal from the photocell at the muzzle range station 18 produces a momentary flashing of the neon light on the rotating disk 345. To junction 476 (see Figure 13 near transformer 471) there is connected a resistor 483 which is connected to the ground line 455 at junction 484. The cathode of the full wave rectifier tube 478 is powered by secondary winding 485 of transformer generally designated 486. The primary 487 of the transformer is connected to alternating current feeders 438 and 444.

In an analogous manner, a signal received on line N from the photocell station located at the target range station 22 is applied to terminal 489 of the microswitch II. When the microswitch is in the "Range" position, Figure 18, the signal is communicated to microswitch terminal 490, whence the circuit continues through resistor 481 and condenser 492 to the primary 493 of a transformer generally designated 494, and thence to ground line 455. One terminal of the secondary 495 of the transformer is connected by line 496 to the negative terminal 424 of power supply No. 2T shown over the bracket 402 and is likewise connected through condenser 497 to the ground line 455. The opposite terminal of the secondary 495 is connected directly to the grid 498 of the gas-filled trigger tube 499. This trigger tube is identical with that illustrated at 461 and includes an indirectly heated cathode 500, grid 498 and anode 501. The anode is connected through line 502 and resistor 503 to the positive terminal 426 of power supply No. 2T and is connected through condenser 505 to the ground line 455. The cathode 500 is connected through the primary 506 of the transformer 507 to the ground line 455. The secondary 508 of transformer 507 is grounded at

Junction 474, the opposite terminal being connected through line 508 and junction 510 to the anode 512 of full wave rectifier tube 478. A resistor 513 is connected between junction 510 and junction 484 on the ground terminal.

Thus, when a signal is received from the target range station 22, the sharp, negative wave received on line N is communicated through the microswitch II to the transformer primary 493 which serves to induce a similar sharp positive wave in the transformer secondary 495, thus swinging the normally negative grid 498 of the trigger tube 499 to the positive condition causing that tube to become conductive. This causes the charge on condenser 505 to be dissipated through the primary 506 of the transformer 507, thereby inducing a sharp signal wave in the secondary 508 of the transformer. The signal voltage, as in the case of transformer 471, is communicated to the circuit extending from ground 458 to junction 474, thence through transformer winding 508, line 509, anode 512 of the full wave rectifier tube 478, cathode 479 of that tube to junction 488, thence through resistor 481 and line D to the neon light 348 of the revolving disc 345, the neon light being grounded at the disk.

In Figure 14 the upper and lower parts of the diagram include two amplifiers, amplifier No. 1 under the bracket 515 and amplifier No. 2 over the bracket 516. Each of these amplifiers includes a pre-amplifier section, namely pre-amplifier No. 1 and pre-amplifier No. 2. The pre-amplifiers are housed in grounded, shielded cases shown by the dotted line outline 397 and 398 previously referred to.

Referring to amplifier No. 1, a power pack, not illustrated, is connected across the potentiometer resistor 517, through switch 735. The resistor has a ground at 518 and has a negative terminal 519 of about 110 volts negative, a 125-volt positive tap at 520, a 180-volt positive tap at 521 and a 240-volt positive tap at 522 which is the positive output terminal. A bridging resistor 523 is connected across the ground and negative terminals and is provided with an intermediate voltage tap 524.

The input to the pre-amplifier section of amplifier No. 1 is by way of the shielded cable 383 which is connected to the terminals 525 and 526 of microswitches VII and VIII, respectively. Contacts 527 and 528 of these microswitches are grounded. Movable contact 528 of microswitch VIII is connected via line 530 to the movable contact 532 of microswitch III. The movable contact 536 of microswitch VII is connected to one terminal of the primary winding 534 of the transformer 535, the other terminal of that winding being connected to ground line 540. The secondary winding 537 is connected to the ground line 540, and the opposite terminal is connected through junction 541, inductance 542 and junction 543 to the control grid 545 of the pentode amplifier tube generally designated 546.

Tube 546 includes a cathode 547 which is connected through junction 548 to the suppressor grid 549 and from junction 548 there is a parallel circuit composed of resistor 550 and condenser 551 extending to the ground line 540. A pair of condensers 552 and 553 are connected from junctions 543 and 541, respectively, to the ground line 540. The grid 554 is connected through condensers 555 and 556 in parallel to the ground line 540 and is connected by way of junction 558 and through resistor 559, junction 560 and line 561 to the positive terminal 522 of the power supply.

The anode 562 of the pentode tube 546 is connected by line 563 through junction 564, condenser 565 and resistor 566 to the ground line, and a branch circuit extends from junction 564 and resistor 568 to junction 569 and thence to positive terminal 522 on the power supply.

The four-element amplifier tube generally designated 569 includes an indirectly heated cathode 570, a control grid 571, second grid 572 and anode 573. The cathode 570 is connected through junction 574 and through resistor 575 and condenser 576, in parallel, to the ground line 540. The grid 572 is connected through line 577 to tap 520 of the power supply. Anode 573 is connected to junction 579 and thence through resistor 580 to tap 521 on the power supply. The grid 571 is connected to a variable tap 581 on resistor 586 by which the gain of this tube may be varied. From 579 a circuit extends through condenser 582 to junction 583 and thence through resistor 584 to variable tap 524 on resistor 523. The variable tap 524 regulates the bias of tube 585.

Tube 585 is a gas-filled trigger tube of the thyratron type and includes an indirectly heated cathode 586, control grid 587 and anode 588. The grid 587 is connected through resistor 589 to junction 583 and cathode 586 is connected through line 590 directly to ground line 540. The anode is connected to junction 591 whence a circuit extends through resistor 592 to tap 521 on the power supply. From junction 591 a circuit also extends through condenser 593 and resistor 594 to ground line 540. From tap 595 a circuit extends to contact 596 of push button controlled microswitch B. The microswitch B also includes a contact 597 which is connected by way of line 598 to junction 599. The movable contact 600 of the push button controlled microswitch B is connected by line 601 to contact 602 of cam controlled microswitch I.

From junction 591 a testing circuit extends via line 603 through normally open switch 604 and thence through resistor 605 and neon light 606, in parallel, and through condenser 607 to ground line 608.

Amplifier No. 2 shown over bracket 516 is of precisely the same type as amplifier No. 1. The input to the preamplifier portion of amplifier No. 2 is by way of shielded cable 393 which is connected to contacts 609 and 610 of microswitches IX and X, respectively. Contacts 611 and 612 of these microswitches, respectively, are grounded. Movable contact 614 of microswitch IX is connected by means of line 615 to movable contact 617 of microswitch IV, Figure 13. Contacts 618 of microswitch III and 619 of microswitch IV are connected together and grounded at 620. Contacts 621 of microswitch III and 622 of microswitch IV are likewise connected together and to line D at junction 623.

The movable contact 625 of microswitch X is connected to the primary 626 of transformer 627. The primary 626 is connected to ground line 628. The secondary winding 630 of the transformer and condenser 631 are connected in parallel at junction 632 and are connected to ground line 628. From junction 632 the circuit extends through inductance 633 and thence to the grid 634 of the pentode amplifier tube 635. A condenser 637 is connected between junction 636 on the grid lead and ground line 628. The pentode has an indirectly heated cathode 638 which is connected to the screen grid 639 externally of the tube at junction 640, and from junction 640 a circuit extends through resistor 641 and con-

denser 642, in parallel, to ground line 628. From anode 643 a circuit extends over line 644 to junction 645 and thence through condenser 646 and resistor 647 to ground line 628. From junction 645 a circuit extends through resistor 648 to junction 650 and thence over line 651 to the positive terminal 652 of the potentiometer resistor 653. The potentiometer resistor is supplied through switch 734 from an independent power pack of the type described with reference to amplifier No. 1. From grid 654 of pentode 635 a circuit extends through junction 655 and 656 and through condenser 657 to the ground line 628. A condenser 658 is connected between junction 655 and ground and a resistor 659 is connected between junction 654 and 650, and thence over line 651 to positive terminal 652.

The tetrode amplifier generally designated 660 has an indirectly heated cathode 661 which is connected through resistor 662 and condenser 663 in parallel to ground line 628. The control grid 664 of the tetrode is connected to the variable tap 665 of resistor 647 by which the gain of the tetrode amplifier is regulatable. The grid 666 is connected to tap 667 on resistor 653, and the anode 668 is connected through junction 669 and resistor 670, junction 671 to tap 672 on the resistor 653. Junction 669 is connected through a condenser 673 to junction 674 from which a circuit extends through resistor 675 to variable tap 676 on the bias resistor 677. The bias resistor is connected to the ground tap 678 and to the negative terminal 679 of the potentiometer resistor 653, and by varying the adjustment of the tap 676, the bias of the tetrode 660 may be varied. From junction 674 a circuit extends through resistor 680 to the grids 681 of the gas-filled trigger tube 682. The trigger tube has an indirectly heated cathode 683 connected to the ground line 628 and an anode 684 that is connected to junction 685. From junction 685 a circuit extends through resistor 687 to junction 671 and thence to tap 672 on the potentiometer resistor. Likewise from junction 685 a circuit extends through condenser 689 to junction 690 and thence over line 691 to junction 599 from line 691 and continues to terminal 692 of microswitch II. From junction 690 a circuit likewise extends through resistor 693 to the ground line 628.

From junction 599 a circuit extends to terminal 694 of the push button operated microswitch A. Microswitch A has a movable contact 695 which is normally maintained in contact with the stationary contact 696 from which a circuit extends through resistor 697 to tap 698 on the potentiometer resistor 653.

The disjuncture charge circuit, shown over the bracket 700, consists of a resistor 701 and a condenser 702 connected in parallel between junctions 703 and 704. Junction 703 of the parallel circuit is grounded and junction 704 is connected to the movable contact 695 of the push button operated microswitch A.

From junction 685, Figure 14 (the output of amplifier No. 2), a circuit extends over line 705, through normally open switch 706 and thence through resistor 707 and neon light 708, in parallel, and through condenser 709 to ground line 608. Both the neon lights 606 and 708, together with their parallel resistors and a control switch, are testing circuits as indicated.

Figures 17, 18 and 19.—These figures show the position of the manually operated microswitches I through VI and the solenoid operated microswitches VII through IX in the three operating conditions

of the system, namely a "Read" position (Figure 17) when the recorded signals are read, a "Range" position during which the signals are received from the range and recorded on the magnetic element of the revolving disk and a "Disjuncture" position which is a circuit testing condition.

Figures 15 and 16.—The circuit apparatus just described may be embodied conveniently in a panel type mounting as shown in Figures 15 and 16. This mounting includes three main panels 710, 711 and 712. Panel 711 is provided with a manually operable handle 713 which serves, through suitable cams not illustrated, to operate the microswitches I through VI, causing them to close the circuits as shown in Figures 13 and 17, 18 and 19. The three operating positions "Read," "Range" and "Disjuncture" are shown on the front of panel 711. Panel 711 also includes the double throw switch 714 and the meter 427 serving power supplies Nos. 1T and 2T.

Panel 710 includes a voltmeter 716 which indicates the alternating current supply line voltage and a number of control switches 717, 718, 719, 720, 721, 722 and the push button 723. This panel also includes a number of pilot lights 724, 725, 726, 727, 728 and 729. The purposes of these are as follows: Switch 717 controls motor 336 and pilot light 724 indicates when the circuit is in operation. Switch 722 is the general alternating current control switch and pilot light 725 its indicator. Switch 718 controls the plate circuit of tube 499 and switch 719 the filament. These tubes require a long warm-up period. Pilots 726 indicate plate voltage and pilot 727 filament current of tube 499. Switches 720 and 721 control the filament and plate voltages of tube 461, respectively; pilot light 728 indicates the filament current and pilot light 729 indicates the plate voltage of said tube 461.

Panel 712 includes a meter 730 (see Figure 14) which indicates the voltage from ground to terminal 522 (power supply of amplifier No. 1) and from ground to terminal 652 (power supply of amplifier No. 2). Meter 730 is connected through a double throw toggle switch 429, as shown in Figure 14, in order to read either voltage. This panel also includes a toggle switch 734 for turning off and on amplifier No. 2, a toggle switch 735 for turning off and on amplifier No. 1. Switches 735 and 734 are not shown in Figure 14 as they control the alternating current feed to standard rectifier power packs (not illustrated) which in turn are connected to potentiometer resistors 517 and 653. The energization of amplifier No. 1 and amplifier No. 2 is thus controlled by turning on or off the alternating current feed lines to the power packs feeding these amplifiers. Pilot lights 732 and 731 are connected to the power supplies of amplifiers No. 1 and No. 2, respectively, to show energization when switches 735 and 734 are closed.

At the bottom of panel 712 there is an adjustment knob 736 which controls the "gain" regulating contact 665 of the tetrode amplifier 660 and a control knob 737 which controls the "bias" regulating contact 676 on that amplifier stage. There is also included a control knob 738 which controls the "gain" regulating contact 581 of amplifier No. 1 and a control knob 739 for varying contact 524 of the "bias" control of amplifier No. 1. Push button controlled microswitches A and B that are used in the "disjuncture" test operation are also included on panel 712.

Operation

After the system has been energized by closure of the appropriate control switches, the light sources 18 and 20 are illuminated and light falls upon the photocells 105 in each of the photocell and amplifier units 18 and 22. When the ordnance piece 10 (Figure 1) undergoing testing is fired, the projectile travels along the line 11-11 and as it passes the line of sight 70-71 at the muzzle station in the range, light from the light source 16 that has been falling upon the photocell and amplifier 18 is thus momentarily decreased in amount. As the projectile passes the line 73-74 at the target station the light from light source 20 that has been falling upon the photocell 105 in unit 22 is likewise momentarily decreased in amount. The photocells and their amplifiers operate upon decrease in light. The percentage decrease is very small.

Referring to Figure 8, under normal illumination the photocell 105 has a steady current conducting effect and the potential existing between junctions 116 and 128 (lower left in Figure 8) causes a steady current flow from junction 128 through line 129 and photocell, thence through line 136 and junction 137, resistor 121, junction 131 to junction 116 on ground line 118. When the photocell is illuminated steadily, amplifier tube 141 is conductive at a constant value. When the photocell is darkened due to the passage of the projectile, the amplifier tube 141 momentarily becomes less conductive. Under normal steady state conditions current flows from high voltage supply, i. e., contact 3 of the socket 104, through line 176, resistors 175 and 173, junction 170, line 169, plate 146, cathode 142, line 154 to ground line 118. The degree of conductivity of the tube is determined by the negative bias on grid 143 as determined by the bias cell 150. When the illumination falling on the photocell momentarily decreases, the resistance of the cell increases, and there is accordingly a momentary negative voltage wave at junction 137 which is impressed through condenser 138 upon grid line 140 of tube 141. This causes the tube 141 to become less conductive (of greater resistance) and hence the current flowing in its cathode-anode circuit decreases. This produces a momentary positive voltage wave at junction 170 in the plate circuit, and this is impressed through condenser 171 upon resistor 172 and is conducted through line 188 to grid 182 of the amplifier tube 180.

Amplifier tube 180 which is normally conductive at a steady state becomes more conductive due to the positive wave impressed upon its control grid 182. The output circuit of tube 180 extends from terminal 3 of socket 104, through line 176 to junction 177, then through line 215, junction 214, resistors 213 and 211, line 206, to plate 186, cathode 181 and through resistor 193 to ground line 194. The momentary increase in conductivity of tube 180 (which is equivalent to a momentary decrease in resistance of the tube) has the effect of producing a negative voltage wave at junction 207 in the plate circuit 206, and this is impressed through condenser 208 upon line 209 and through it to the control grid 223 of amplifier tube 220.

Amplifier tube 220 is normally conductive through a circuit extending from terminal 3 of socket 104 and through high voltage lines 176 and 215, through resistors 236 and 234, line 231, plate 224, cathode 221, and resistor 229 to ground line 194. The momentary decrease in conduction

tivity of the tube 220 (which is equivalent to a momentary increase in resistance of the tube) has the effect of producing a positive output wave at junction 232 in line 231 as the signal comes through. The output positive wave is impressed through condenser 240 upon line 241 and thence to output terminal 5 of the plug 104A.

Before tracing through the energization of signal in the circuit shown in Figure 9, it may be pointed out that in ordnance testing the wave shape of the signal is equivalent to a relatively high frequency output and that various low frequencies are objectionable. Despite many safeguards against the introduction of low frequencies from the commercial (60 cycle) supply, some signals of this character are present in the circuit. Likewise the muzzle flash of the ordnance piece undergoing testing and explosion flash where an explosive projectile is tested, produces light signals which to some degree find their way into the photoelectric apparatus, and these likewise produce signals of lower frequencies. In order to discriminate against these signals and to favor the desired relatively higher frequency signals, condenser 208 (between tubes 180 and 220) is of small capacity. This condenser with resistor 210 may be considered as a high pass filter which discriminates against the lower frequencies. Thus, even in the amplifier shown in Figure 8 which is mounted directly below the photocell in the physical apparatus (Figures 5 and 6) provision is made for discriminating against further transmission of the undesirable lower frequencies.

The positive output signal wave on terminal 5 is communicated through the plug 104-104A to line 290 of Figure 9 and thence through resistor 292 and normally closed switch 293 to the control grid 287 of the gas-filled trigger tube 284. The grid 287 of tube 284 is connected through resistor 322 to the housing ground line 282. The resistor 324 which is connected to the grid lead at 291 and to tap 325 of the power supply normally maintains the grid 287 negative through resistor 292. The variable tap 325 is adjusted so as normally to maintain the grid 287 negative by an amount slightly less than the incoming positive signal wave on line 290 and hence when the signal is received the grid 287 momentarily swings positive and tube 284 fires through a circuit extending from positive tap 276 on the power supply potentiometer resistor 269, thence through resistor 304, junction 305, anode 288, cathode 285, resistor 296 to ground line 282. Tube 284 which thus becomes momentarily of very low resistance serves to discharge condenser 308 through a circuit extending from ground line 282, resistor 310, condenser 308, line 307, junction 305, through the anode-cathode circuit of tube 284, resistor 296 to ground line 282. When this occurs a wave of very short duration occurs at output terminal 309 and is communicated through line 313 to output terminal 314 on the plug 315.

While tube 284 is non-conductive prior to firing, no current flows through its anode-cathode circuit, and hence there is practically no potential drop across resistor 296 in its cathode circuit, but when the tube 284 becomes conductive and fires, there is a relatively large potential drop across resistor 296. This has the effect of immediately stopping the firing of the tube.

It may be pointed out also that most of the current flowing through the tube when it fires is from condenser 308 due to the relatively high value of resistor 304 and that when switch 293 is open, the tube will fire periodically at a rate de-

terminated by the size of condenser 388 and resistor 304. This serves as a convenient means of testing the operation of the gas tube apparatus since merely by opening switch 293 it is possible to impress upon the output 309 a series of repeated, sharp negative waves. Any deviation from this normal testing response clearly indicates some erroneous operation of the apparatus. Likewise, when switch 293 is opened the input signal on terminal 5 may be tested conveniently by connecting an oscilloscope to the oscilloscope jack 332. The spring terminal 333 of the jack is connected through line 334 to the input signal terminal 5 of plug 104A, the other terminal 335 of the jack being grounded. Thus, by connecting an oscilloscope to jack 332, it is possible to test the incoming signal received at the apparatus of Figure 9 which, in the physical embodiment, is in the base 82 of the stand.

At the station unit 25, Figure 1, the incoming signal from the muzzle photocell and amplifier station 18 is received over line K, and the signal from target station is received over line N. Since it is assumed that the handle 713, Figure 15, has been moved to the "Range" position, microswitches I through VI are thereby manually positioned as shown in Figure 13 (same in Figure 18) and microswitches V and VI thereby control microswitches VII through IX to the corresponding positions as shown in these figures. The signal received upon line K (Figure 13, upper center) is thereby impressed through resistor 451 and condenser 452 upon the transformer primary 453. The incoming signal is a very steep negative wave front and this induces a steep positive wave front in the secondary 457 of the transformer 454 causing the grid 460 of the gas-filled trigger tube 461 to be swung momentarily positive. Tube 461 thereupon becomes conductive and serves as a discharge path for the charge stored upon condenser 465 as previously explained. The sharp surge through the tube 461 passes through the primary 470 of transformer 471 thereby inducing a signal in secondary winding 473 which is transmitted through rectifier tube 478, line D and the microswitches to the No. 1 pick-up coil 378 adjacent the rotating disk 345 through a circuit as follows: From ground 456, Figure 13, a circuit extends through line 455, junction 474, secondary winding 473, junction 476, through line 477 to cathode 479 of tube 478, thence through junction 480, resistor 481, line D to junction 623. The line D from junction 623 extends to the neon light on the revolving disk and hence the light is flashed but this is incidental to the recording of the signal on the disk 345 for the circuit branches at 623 on line D and extends to contact 621 of microswitch III and to contact 622 of microswitch IV. Since the movable contact 617 of microswitch IV is in engagement with contact 618 (that is grounded at 620), no circuit is completed from contact 622 of microswitch IV, but a circuit is completed from contact 621 of microswitch III, through movable contact 532 and thence over line 530 to movable contact 529 of microswitch VIII which is then in the position to engage its contact 526 from which the circuit continues over shielded cable 383 to No. 1 pick-up coil 378, which now acts as a recording coil and produces a magnetic signal on ring 347 of disk 346. It may be noted that at this time movable contact 536 of microswitch VII is in engagement with its ground contact 526 thereby preventing any leakage of the high frequency signals across into the pre-amplifier of amplifier No. 1 which

might occasion erroneous operation of that amplifier.

As the projectile passes line 73-74 at the target station it actuates the photocell and amplifier 22, Figure 1, thereby initiating a signal which comes into the station unit 25 via the "target" line N, Figure 13. Since microswitch II is in engagement with its contact 488, the sharp, negative wave signal is impressed through resistor 481 and condenser 482 through the transformer primary 483 to ground line 485. This induces a sharp positive wave in secondary 485 of transformer 484, thus initiating the discharge through the gas-filled trigger tube 488, in exactly the same manner as for tube 461. The charge upon condenser 505 which had been built up through resistor 503 during the time tube 488 was non-conductive, is thereby discharged through tube 488 and through the primary 506 of transformer 507. Consequently, a voltage is induced in secondary 508 which is conducted through rectifier tube 478 to junction 623 of the line D, where it is distributed to the neon light 349 causing it to flash and also through microswitch III to No. 1 pick-up coil 378. This causes the energization of the pick-up coil, which, acting again in its recording capacity, makes a second magnetic record on ring 347 of disk 346. Since the disk is rotated by the synchronous motor 336, the passage of the projectile thus causes two magnetic records to be recorded on the magnetizable rings 347 of the disk 345 at angular spacings determined by the speed of the disk and the speed of the projectile. The record may be "played back" by moving the operator handle 713 to the "Read" position.

Read position.—With the handle 713 in the "Read" position, microswitches I-VI are moved to the position shown in Figure 17 and in that position the switches V and VI actuate switches VII-X to the positions also shown in Figure 18. It will be recalled that both of the magnetic records on the rotating disk 346 were impressed by means of No. 1 pick-up coil 378. As the disk rotates, however, the magnetic records on the disk serve at each revolution to induce slight electromotive forces in both of the pick-up coils 378 and 385. Whenever a voltage is thus generated in one of these coils, it is amplified either through amplifier No. 1 or amplifier No. 2, depending upon the pick-up coil in which the voltage is generated. Since the action is identical for both pick-up coils and amplifier, only one need be described.

Assuming that the leading magnetic record passes under No. 1 pick-up coil 378, the voltage thus generated is transmitted by way of shielded cable 383 through microswitches VII to primary 534 of transformer 535 which induces a voltage in secondary 537 that is applied to the grid of tube 546. The incoming signal from the pick-up coil is an approximately symmetrical wave, but tube 546 is biased so that the output in its plate circuit 563 is predominately negative, the positive portion of the wave being suppressed at least in part. The output of tube 546 is transmitted through condenser 565 and resistor 566 to the grid 571 of tube 569. Then tube 569 is normally conductive but becomes less so when the negative signal is applied to its grid 571 thus causing a positive signal at junction 579 which is transmitted through condenser 582 to the grid 581 of the gas-filled trigger tube 585. It may be pointed out that as in the photocell amplifiers (Figure 8) condenser 582 serves to suppress the

lower frequencies and accordingly the control voltage on the grid 581 of the trigger tube is very sharp. The trigger tube 585 is normally non-conductive but becomes conductive due to the incoming signal on its grid 581. The discharge through tube 585 is principally from the condenser 593 since resistor 592 is of a sufficiently high value that insufficient current is passed to maintain discharge of the trigger tube. Accordingly, as the charge on condenser 583 is dissipated tube 585 again assumes the non-conductive condition. The discharge of condenser 593 accordingly generates a very sharp negative voltage at junction 595 which is conducted through the normally closed push button control microswitch B and through microswitch I, resistor 451, condenser 452 and primary winding 453 of transformer 454 to ground. This induces a signal in the secondary 457 which eventuates in the operation of the neon light 449 on the revolving disk 445 through an operation precisely the same as when the incoming signal is received from the range, as previously described. Thus, as the leading magnetic record passes under the No. 1 pick-up coil, the neon light is caused to flash.

Similarly the trailing magnetic record passes under No. 1 pick-up coil and likewise causes the neon light to flash but since the disk has now proceeded around through an angularity equal to the angularity between the magnetic records on the disk, the neon light flashes occur in angularly disposed relationship. It will be assumed that the adjustment of knob 375 is such that No. 1 pick-up coil is located at an angle in respect to the No. 2 pick-up coil which is greater than the angle between the magnetic records on the disk 347. When this is true, the trailing magnetic record approaches the No. 1 pick-up coil and causes the second signal flash before the leading magnetic record passes under the No. 2 pick-up coil. A third flash occurs when the leading magnetic record passes under No. 2 pick-up coil, and the third flash occurs at an angle from the second flash which is equal to the difference between the angle between the pick-up coils and the angle between the magnetic flashes. Thereafter, as the trailing magnetic record passes under the No. 2 coil, a fourth flash occurs. By rotating the knob 375 so as to decrease the angle between the pick-up coils, the two middle flashes (second and third) are brought gradually together until they coincide. When this occurs the operator knows that the magnetic coils are set at the same angle as the magnetic records on the rotating disk and by simply reading the angularity on scale 342B and knowing the rotary speed of the magnetic disk, it is possible to calculate the time elapsed between the flashes. Usually, the scale 342 is calibrated directly in feet per second for convenience.

The recording and reading presupposes a constant frequency impressed upon the driving motor 336. In order to provide for correction if the frequency varies, there is provided a frequency meter 396 and the adjustment screw 388 which serves to move magnetic coil 385 angularly in the direction of the double arrow 390. In the event of frequency decrease this is equivalent to a decrease in the rotary speed of the disk 346 and therefore for decreased frequencies there will be a smaller angle between the magnetic records on the disk 346 than for higher frequencies on the driving motor. By calibrat-

ing the scale 381 adjacent coil 385 in terms of frequency, the position of the No. 2 coil may be decreased or increased as frequency variations occur and are indicated by frequency meter 396. If desired, a power line of regulated and closely controlled frequency may be used for operating motor 336, but usually ordinary good commercial service suffices.

Thus, it will be observed that the two angularly spaced magnetic records in passing under each pick-up coil cause a pair of flashes of the neon light 349 and that the two pairs of flashes may be moved with respect to each other until the adjacent flashes of the two pairs coincide. When this condition exists the angular spacing of the pick-up coils is the same as the angular spacing of the magnetic records.

Disjuncture.—The Disjuncture condition is essentially an apparatus testing arrangement by which errors may be eliminated. When a magnetic record passes under a pick-up coil, the flash is caused to occur in the neon light, as previously explained, but there is no way of telling whether the flash occurs when the pick-up of the magnetic record is under the center of the coil or whether it occurs when the record is displaced one way or the other from the center line of the coil. There are unavoidable physical variations between the two pick-up coils 378 and 385 and other variation factors occur which are due to changes in temperature and operating conditions of the various circuits and thermionic tubes. The Disjuncture circuit condition is provided as a test whether the magnetic records are in fact under the coils when the flashes occur. To carry out this operation the handle 713, Figure 15, is moved to the Disjuncture position which causes switches I-VI to be moved into the position shown in Figure 19 and switches VII-X are then magnetically actuated to the positions as also shown in Figure 19. Referring to Figure 13 it will be noted that when the movable contact of microswitch A is normally in contact with contact 696, a positive potential is impressed on contact 696 through resistance 697. This voltage is communicated through movable contact 695 of switch A to junction 704 and thence through resistor 791 and condenser 702, in parallel, to ground terminal 703. This serves to charge condenser 702 to a predetermined condition. With the microswitches I-V in the Disjuncture position and microswitch A in the condenser charging condition, just mentioned (contact 695 engaging 696), microswitch B is pushed so as to bring its movable contact 600 into engagement with its stationary contact 591. Microswitch A is then pushed which serves to connect terminal 704 to contact 694 and simultaneously condenser 702 discharges through resistor 701 for a time interval determined by the constants of the resistor-condenser network. The voltage at point 704 is thus placed upon line 691 at junction 599 and also upon line 601 by way of microswitch B which is held in the depressed condition during this operation. Therefore, the primaries 453 and 493 of transformers 454 and 494, respectively, are simultaneously energized, tubes 461 and 499 simultaneously become conductive and the double strength signal is transferred through the rectifier tube 478 from both anodes at the same time to junction 623 on the line D. The neon light 345 is flashed but this is incidental for the signal is also transferred by way of microswitch III and IV to both lines 530 and 615 simultaneously and thence by way of microswitches VIII and IX, re-

spectively, to the No. 1 pick-up coil 378 and No. 2 pick-up coil 385 so as to energize both of the coils simultaneously. Hence, there is placed upon the magnetic ring 347 revolving disk 345, two zones of magnetization which are angularly displaced by an angle equal to the angle between the No. 1 pick-up coil and the No. 2 pick-up coil.

The operator control handle 713 is then moved to the Read position and the record is read. If everything is operating perfectly when such a record is played back, the neon light will show three flashes. Actually, if everything is right there are two pairs of flashes but adjacent flashes of the two pairs coincide so that the signal actually appears as three flashes of light angularly disposed, the two angles between adjacent flashes being equal to the angle between the two pick-up coils.

If the signal does not consist of three flashes, as above described, but instead shows two pairs with the middle two close but visibly displaced, some malfunctioning exists. This can usually be corrected by varying the gain and bias of amplifiers No. 1 or No. 2 or both. By so doing the adjacent flashes of the two pairs can be brought into juxtaposition. In this manner the instrument is adjusted so that the angular position between the pick-up coils as read on the scale 342 will actually be the angular distance between the magnetic records on the revolving disk.

As many apparently widely different embodiments of this invention may be made without departing from the spirit and scope thereof, it is to be understood that we do not limit ourselves to the specific embodiments herein except as defined by the appended claims.

What we claim is:

1. A timing apparatus for recording and indicating short time intervals comprising a record and indicating means including a circular member of magnetizable material and a quick responsive signal lamp both mounted for rotation in a circular path thereon, motor means for rotating the record and indicating means at a constant rate, a pair of electromagnetic elements movable relative to each other located adjacent the circular member in cooperative electromagnetic relationship, a pair of incoming signal carrying circuits, a pair of amplifier networks, one for each electromagnetic element and switch means responsive in one condition of operation to communicate incoming signals received on either incoming signal circuit to one of the electromagnetic elements to record on the magnetizable member signals received on either incoming signal circuit and responsive in another condition of operation to communicate signals generated by

either electromagnetic element through its corresponding amplifier network to the quick responsive signal.

2. The apparatus of claim 1 further characterized in that in a third condition of operation of said switch means a testing signal charge is communicated simultaneously to both electromagnetic elements.

3. The apparatus of claim 1 further characterized in that the electromagnetic elements are movable relative to each other while maintained in cooperative relation to the magnetizable element.

4. The apparatus of claim 1 further characterized in that each amplifier network includes a thermionic amplifier tube and a gas-type trigger tube responsive thereto.

5. The apparatus of claim 1 further characterized in that each of said amplifier networks includes an extremely sensitive shielded section and said switch means is located partly in each shielded section and partly without, the switch means part without the shielded section being manually operable and the switch means part within the shielded section being magnetically operated responsive to the operation of the switch means part without said section.

Certificate of Correction

Patent No. 2,482,184

September 20, 1949

HARRY WILLIAM HOFFMAN ET AL.

It is hereby certified that errors appear in the printed specification of the above numbered patent requiring correction as follows:

Column 11, line 59, for "conmpleted" read *completed*; column 15, line 16, for "junction 654" read *junction 656*;

and that the said Letters Patent should be read with these corrections therein that the same may conform to the record of the case in the Patent Office.

Signed and sealed this 11th day of April, A. D. 1950.

[SEAL]

THOMAS F. MURPHY,
Assistant Commissioner of Patents.
